Gilbert C. Whitney

UNITED STATES PATENT OFFICE.

GILBERT C. WHITNEY, OF NEW YORK, N. Y.

RAILWAY-TRAFFIC-CONTROLLING SYSTEM.

Application filed March 5, 1924. Serial No. 697,129.

This invention relates to railway traffic controlling systems in general wherein means are provided for the control of trains by signals and in particular to novel means for controlling said signals by virtue of controlling its track circuit from additional points aside from or in combination with the usual and well-known interlocking systems.

On railroad systems it is customary to provide what is termed a track model, illuminated track indicator or other means suitably located, for example, in a tower, block station or dispatcher's quarters, to provide information as to the position and movement of trains. In an application filed and to co-pend with this application (Serial No. 702,262 now) I have disclosed a novel means for indicating the movement and position of trains and herein I am disclosing novel means for inexpensively incorporating, into the system of said co-pending application, a point of control, for example, from a dispatcher's quarters, to govern as well as indicate the position and movement of trains. The foregoing indicates the general object of this invention and additional objects will be disclosed as the specification progresses and I will point out the novel features in the appended claims.

I have provided five figures to clearly portray the application of my invention to existing track and signal circuit design and wherein Fig. 1 shows the elements of my system as set forth in a system wherein the presence of a train on a track circuit is indicated by the absence of an electric light or other similarly appropriated means in the indicator system; Fig. 2 shows the same or similar elements as applied in a system wherein the presence and movement of a train on a track circuit is indicated by the appearance or variation in brilliancy of an electric lamp or other similarly appropriated means in the indicator system; and Fig. 3 shows the same elements involved but combined with a lever controlled signal. All three figures set forth the novelty of this disclosure of incorporating into the indicator system a dispatcher's controller. Figs. 4 and 5 illustrate modified means of connecting up the principal elements involved. Similar elements and parts are designated by the same characters in all of the figures.

Referring to Fig. 1, a track section is set apart by insulated joints 8 the track rails of the section being identified by the reference characters 6 and 7. At one end of said track section a transformer 9 is shown connected to rails 6, 7, by means of track wires 10, 11, resistance 12 and fuse 13. Transformer 9 is the medium, when energized by means of wires 14, 15, from power wires 16, 17, connected to the source of energy alternator 18, by which appropriate current supply, when a train is not present, is transmitted over said track rails to track wires 19, 20, fuse 21 and resistance 22 to winding 23 of relay 24. Winding 25 of relay 24 receives energy by means of wires 26, 27, from power wires 16, 17, and thus far the whole constitutes the well known alternating current track circuit wherein most of the energy required for the operation of the track relay 24 is supplied locally and only a small part or activating current is transmitted over the track rails. Also in conventional manner I have shown signal 32-33 controlled by contact 28 of relay 24 and control wires 29, 30 and 31. The track and circuit and signal and circuit outlined above is intended simply as a structure and I make no claims of invention in connection therewith—it is shown only to provide a basis for my invention.

This invention consists in connecting the primary winding 35 of transformer 34 in multiple with resistance 22 as shown and so that part of the current flowing to winding 23 of relay 24 passes through said winding 35. Inductively coupled to winding 35 is shown secondary winding 36 and the current induced therein is carried over transmission wires 37, 38, to the dispatcher's quarters and there energizes winding 40 of transformer 39 by means including wire 43 and dispatcher's multiple point control switch 44. Inductively coupled to winding 40 is shown winding 42 and the current induced therein becomes available and is used for energizing indicator lamp 45. From the above it will be clear that when the track section is not occupied it will be indicated by the fact of lamp 45 being lighted and that when the track section is occupied lamp 45 will not be receiving sufficient energy to cause the same degree of illumination and therefore the condition of lamp 45 indicates the condition, with respect to the occupancy and non-

occupancy of the track section. Associated with control switch 44 is shown a resistance 46 which I use to provide despatcher's control of signal 32-33 and at the same time 5 retain track section indication. To control signal 32-33 the despatcher moves switch 44 out of engagement as shown and into position to contact 47—this inserts resistance 46 into the transmission circuit included with 10 wires 37, 38, and less current flows therein resulting in lower induced current supply to lamp 45. As a result of lessened current flow in the transmission circuit the current flow in winding 35 of transformer 34 and 15 consequently to relay winding 23 is lowered, by virtue of the increased choking effect in winding 35, and relay 24 opens thus causing contact 28 to open with resultant change in the signal aspect displayed. From the foregoing 20 it will be clear that winding 35 acts as a current limiting device to limit the flow of current to winding 23 of relay 24 (Figs. 1 and 2) and to limit the flow of current in the circuit which controls relay 49 (Fig. 3) 25 and further that, by virtue of winding 36 of inductive coupling 34, the condition exists whereby the despatcher's switch 44 and resistance 46 combine with the characteristics of winding 35 for the control of the corresponding track circuit (Figs. 1 and 2) and the corresponding relay 49 (Fig. 3). It is 30 further pointed out that the despatcher's receiver transformer may act as an impeding element in substantially the same manner as 35 transformer 34. I show contact 48 on despatcher's control switch for the purpose of making a complete opening in the transmission circuit.

In Fig. 2 I have shown an application 40 of my invention to a track section in a manner so that the indicator lamp 45 is normally out or lowered in brilliancy except when the track section is occupied and the increased current required for the change in 45 illumination of lamp 45 is provided by virtue of the train wheel shunt on track rails 6, 7, causing increased current flow from transformer 9 all as disclosed and claimed in my previously referred to co-pending application and explanation is here given only 50 to show operation of despatcher's control switch 44 operating in combination therewith. In connection with Fig. 2 it is to be noted that despatcher's control of signal 32-33 is brought about by reducing the current supplied to winding 23 by virtue of 55 the choking effect set up in winding 35 of transformer 34 when the transmission circuit included with the wires 37, 38, is affected 60 due to being opened or having resistance 46 added thereto at the despatcher's control switch. It is believed that further explanation in connection with Fig. 2 is unnecessary.

Owing to the fact that on some railroads 65 some of the towers controlling the interlock-

ing signals are closed part of the time it is desirable to arrange a simple means for despatcher's control without affecting the track circuit and other signals controlled thereby and in Fig. 3 I have shown a transmission 70 circuit included with wires 37, 38, connected to transmitter transformer 34 the primary winding 35 of which is included in the control circuit of relay 49 and at the despatcher's quarters the same elements are involved 75 and in the same relation as I have explained in connection with Figs. 1 and 2. It should be noted that lever 50 located in the interlocking tower remote from the despatcher controls signal 32-33 by virtue of 80 relay 49 controlling wires 29, 30. It will also be noted that indicator lamp 45, when lever 50 is reversed as shown, shows the condition 85 of the track section because of relay 24 having control, in combination with lever 50, of relay 49. It will be understood that unless despatcher's controller 44 is closed as shown sufficient current to energize relay 49 cannot flow.

Attention is directed to the following 90 facts:

1st. That the despatcher's indicator lamp conveys its indication by virtue of change in degree of illumination and that said change need not be between definite extremes 95 to be operative.

2nd. That the major portion of current in winding 23 of relay 24, Figs. 1 and 2, is carried by the winding 35.

3rd. That resistances 12 and 22 may be 100 displaced by reactances, or eliminated (as shown in Fig. 5) and that the fuses 13 and 21 are not an essential part of my invention and may be omitted without affecting the 105 operation thereof. Reactance may be substituted for resistance 46.

4th. That despatcher's control is effective without indicator lamp 45.

5th. That the indicator and control system 110 are insulated from the signal system.

6th. That the current requirements of my system are comparatively very small; that I have produced successful and reliable operation in service by inexpensive 5 watt transformers; 1 watt lamps, telephone switches 115 and No. 19 A. W. G. twisted pair paper insulated telephone cable so that my system is extremely cheap to install.

7th. That I may substitute a movable indicator in place of lamp 45. 120

8th. That I may eliminate transformer 39 and connect indicator directly into transmission circuit with despatcher's switch 44 as shown in Fig. 5.

9th. That while I have illustrated winding 125 23 as cooperating with winding 25 to produce mechanical operation of a contactor it will be understood that I may use the effects produced in winding 23 to inductively energize another winding. 130

10th. That I may vary the amount of current flowing in winding 35 by varying the amount of resistance (or reactance) 46 inserted in circuit 37, 38.

5 11th. That variation in current flowing in indicator element circuit due to resistance 46 being inserted in the transmission circuit is an indication of reduced current flowing to winding 23 and therefore may be considered 10 to be an indication that despatcher's control of the track circuit has been effected.

12th. That I may couple (inductively) transmission circuit 37, 38, into wires 26 or 15 27, and thus control winding 25 in lieu of winding 23.

13th. That, whereas means in the form 20 of an impeding element (for example resistance 12, Fig. 2) is required to prevent the train wheel shunt being a short-circuit on transformer 9 the same may be substituted by winding 35 of transformer 34 (see Fig. 5) in which event the energy required for the operation of my system is that which would otherwise be dissipated in 25 the form of heat in the impeding element and therefore when arranged as above indicated no additional power equipment or expenditure for current supplied is required.

14th. That the system operates with a 30 minimum of parts and thus to effect a minimum expense in maintenance cost.

Obviously, various types of track circuits, 35 both alternating and direct current, of single and double rail type may be employed in combination with my invention by making the obvious appropriate changes well known to any one ordinarily skilled in this art and I desire to have it understood, therefore, that the arrangements and illustrations 40 which I have shown and described are merely illustrative and do not exhaust the various embodiments and forms which my invention may take in practice.

Having thus described my invention I 45 claim and desire to secure by Letters Patent:

1. A plurality of track circuits each including a source of energy a track relay and a current limiting device for each track circuit, and means inductively coupled to each track circuit to provide control of the corresponding track circuit and track relay, said means acting in combination with said current limiting device.

2. A plurality of track circuits each including a source of energy a track relay and a current limiting device for each track circuit, an indicating element for each track circuit, and means inductively coupled to each track circuit to provide control of the corresponding track relay and indicating element, said means acting in combination with said current limiting device.

3. A plurality of track circuits each including a source of energy a track relay and a current limiting device for each track cir-

cuit, and means inductively coupled to each track circuit to provide control of the corresponding track circuit, said means acting in combination with said current limiting device.

4. A plurality of track circuits each inductively coupled to indicating elements, and means including a resistance inductively coupled to each track circuit to provide control of the corresponding track circuit and 75 indicating element.

5. A track circuit inductively coupled to an indicating element, and means including an electrical resistance to provide variable control of said track circuit and said indicating element, said indicating element arranged for indicating the presence of a train on said track circuit by increase in energization of 80 said element.

6. A track circuit inductively coupled to an indicating element, and means including a resistance to provide variable control of said track circuit and said indicating element, said indicating element arranged to indicate the presence of a train on said track 90 circuit by increase of current flow in a part of said track circuit.

7. In a railway traffic controlling system including a plurality of track circuits, a source of energy a track relay and a current limiting device for each track circuit, and means inductively coupled to each track circuit to provide control of the current supplied to the track winding of each track relay, said means acting in combination with 100 said current limiting device.

8. A plurality of track circuits inductively coupled to corresponding indicating elements, and operable means arranged to provide control of each track circuit, the respective indicating element arranged to act as an indicator for said track circuit, and for indicating that the means when operated has been effective to produce control of the respective track circuit.

9. In a railway traffic controlling system including a section of railway track, a source of current connected across the track rails of said section to form a track circuit, means at either end of said section to receive current from said source, individual means inductively coupled to said system to provide control of the current in said track circuit, and indication means inductively coupled to said system and influenced by train 115 wheels traversing said section.

10. A track circuit including a transformer, a transformer connected in series therewith, and a switch connected in series with the secondary of the second mentioned transformer to control the supply of current to the track circuit.

11. A track circuit including a transformer, a transformer connected in series therewith, and a switch and resistance connected 120

- in series with the secondary of the second mentioned transformer to variably control the supply of current to the track circuit.
12. A track circuit including a transformer, a transformer connected in series therewith, and a switch and an impeding element, said switch and impeding element variably controlling the current supply in said track circuit.
13. A circuit controlled by the wheels of a train and inductively coupled to an indicating element, and a switch arranged to provide control of said circuit, said indicating element arranged to act as an indicator for said circuit and for indicating that the switch when operated has been effective to produce control of said circuit.
14. A circuit controlled by the wheels of a train and by means including an indicating element and a switch, said means inductively coupled to said circuit.
15. A circuit controlled by the wheels of a train, a second circuit including an indicating element a switch and at times a resistive element, said second circuit inductively coupled to said first circuit, said indicating element controlled by said wheels and by said switch.
16. A circuit controlled by the wheels of a train, a second circuit including an indicating element a switch and at times a resistive element, said second circuit inductively coupled to said first circuit, said switch and resistive element controlling the current flow in said first circuit.
17. In a railway traffic controlling system including track sections and an electric circuit traversing each track section, an individual despatcher's control means inductively coupled to each section, and indication means inductively coupled to said despatcher's control means, said indication means influenced by said electric circuit and by said control means.
18. In a railway traffic controlling system including track sections and an electric circuit traversing each track section, despatcher's control means inductively coupled to said electric circuit, and an indication lamp inductively coupled to said despatcher's control means, said indication lamp influenced by said electric circuit and varying in brilliancy as the train moves on said track section.
19. In a railway traffic controlling system including track sections and an electric circuit traversing each track section, a reactive device included in said electric circuit for each track section, despatcher's control means inductively coupled to said reactive device, and an indication lamp influenced by each reactive device and varying in brilliancy as the car moves on said track section.
20. In a railway traffic controlling system including track sections and an electric circuit traversing said sections, despatcher's control means inductively coupled to said electric circuit, and an indication lamp inductively coupled to said despatcher's control means, said indication lamp varying in brilliancy responsively to the car wheel movement on said track section.
21. In a railway traffic controlling system including track sections and an electric circuit traversing each section, a reactive device included in series in said electric circuit, despatcher's control means, and indication means, said despatcher's control means and said indication means inductively coupled to said circuit.
22. In a railway traffic controlling system including track sections and an electric circuit traversing each track section, an individual despatcher's control means inductively coupled to each circuit, and indication means for each section, said indication means influenced by train wheels traversing said section.
23. In a railway traffic controlling system including track sections and an electric circuit traversing each track section, a signal for governing train movement in to each track section, means for remotely controlling each signal, and means for synchronously indicating train movement in each track section.
24. In a railway traffic controlling system, a track circuit including a source of energy and a current limiting device, and despatcher's control means, said means inductively coupled to said track circuit and acting in combination with said device to control the current flow in said track circuit.
25. The claim set forth in claim 24, said track circuit also including a track relay and said track relay controlling an automatic block signal system.
26. In a railway traffic controlling system including track sections and an electric circuit traversing the rails of each track section, a source of energy for supplying current to each circuit, despatcher's control means for remotely controlling each circuit, and means for synchronously indicating train movement on said rails, said control means and said last mentioned means adapted to act simultaneously.

Signed at New York city in the county of New York and State of New York this 3rd day of March A. D. 1924.

GILBERT C. WHITNEY.
